UNITED STATES PATENT OFFICE

ADOLPH M. SCHICK, OF WHEELING, WEST VIRGINIA, ASSIGNOR OF ONE-FOURTH TO
E. G. VOLTZ, OF WHEELING, WEST VIRGINIA

ELECTRIC FAN

Application filed June 13, 1930. Serial No. 460,869.

This invention relates to electric fans, and it has for its primary object to provide a fan adapted for continuous rotation and embodying means whereby may be controlled both the direction and the speed of rotation.

A further object of the invention is to provide, in association with an electric fan, a series of blades or vanes against which currents of air created by the fan engage in such manner as to cause rotation of the fan, said blades being arranged for adjustment to control both the speed and direction of rotation.

A still further object is to provide, in association with the blades and the adjusting mechanism, means for cushioning said blades to prevent objectionable vibration and rattling of the latter.

In describing the invention in detail, reference is herein had to the accompanying drawings, in which—

Figure 1 is a front elevation of an electric fan embodying my invention;

Figure 2 is a partial side elevation of the same;

Figure 3 is a section on line 3—3, Fig. 1.

Figure 4 is a longitudinal section of a portion of the fan support illustrating the rotary contactor, the section being taken on line 4—4, Fig. 2;

Figure 5 is an enlarged detail section showing the blade-cushioning means; and—

Figure 6 is an enlarged detail view of the adjusting-rod tensioning means.

Referring to said drawings, 1 designates an electric motor which has mounted on the rotor 2 thereof a bladed fan 3 of any preferred type. Said motor is mounted upon the outer end of an upright shaft 4 which is journaled for rotation in a socket 5 provided therefor in a supporting standard 6. Said standard may have an integral base 7 adapting it for seating upon a table or other flat surface, or, in reverse position, it may form a part of a pendent ceiling fixture. The socket-received end of the shaft 4 preferably rests upon a ball 8 disposed at the inner end of the socket.

Mounted in a socket or recess 9 disposed in concentric relation to said socket 5 is a hous-

ing 10 for ball bearings, and engaged with the inner face of said housing is an annular shoulder 11 formed on said shaft 4, the inner end portion of said shaft having a greater diameter than its outer end portion.

Mounted in a socket 12 of still greater diameter than said socket 9 and concentric therewith is a plate 13 of suitable insulating material, as fiber, which constitutes the stationary member of a contactor, the same being suitably secured in place, as by screws 14. Carried on the outer face of said member 13 are two concentrically disposed copper rings 15 and 16 to which are attached conductors 17 and 18 for electric current, said conductors leading through bores or passages provided therefor in said standard 6 and the member 13, as shown in Fig. 4. The rotary member 19 of said contactor is fixed to the shaft 4, as by a pin 20, and carries brushes 21 and 22 which, in rotation thereof, make wiping contact with said rings 15 and 16, respectively, said brushes having connection with conductors 23 and 24 leading to the motor.

Mounted in enclosing relation to the fan is a guard or cage 25 which includes a circumferential metal rim 26 about its face portion. Said rim carries interiorly thereof a plurality of fixed oppositely disposed socket pieces 27 in which are mounted for rotary movement trunnions 28 formed on the inner edge portions of the opposite ends of a plurality of sheet metal vanes or blades 29, the arrangement of said socket pieces being such that the therein mounted blades are disposed vertically in spaced parallel relation, as shown.

Mounted and longitudinally shiftable in one side of said rim 26 is one end of a horizontal rod or shaft 30 which is directed through said blades 29 intermediate the inner and outer edges of the latter. Interposed between each of the opposite sides of each blade and an adjacent fixed member, as a collar 31, carried by said rod 30 is a light rod-encircling spiral spring 32. Said springs exert yielding pressure upon said blades and serve to cushion the latter to the extent that vibration due to air currents or blasts emanating from the fan and striking said blades

is prevented. The opposite end of said rod is attached to the rim 26 by means of a retractile coil spring 33, as is best shown in Fig. 6. The first mentioned end of said rod 5 is screw threaded and projects outwardly through the rim 26, and adjustably mounted on said end is a hand wheel 34 or an equivalent device whereby said rod may be drawn longitudinally in a direction against the tension of the spring 33 for adjusting the blades 10 to or toward the full line position shown in Figs. 3 and 5; or whereby, upon rotation in the opposite direction, the spring 33 is permitted to retract for shifting said blades to 15 or toward the dotted line position shown in said Figs. 3 and 5.

As is manifest, by rotation of said hand wheel the rod may be shifted to incline said blades to any extent required, as between the substantially extreme full and dotted line positions indicated in Figs. 3 and 5. Moreover, it is evident that the direction of rotation imparted to the shaft and the thereby-carried parts is dependent upon the direction in which said blades are inclined; also that the speed of rotation is wholly dependent upon the angle of inclination of said blades. Said blades may have their outer edges laterally curved more or less in one direction or the other, thus to increase the resistance offered by the blades to blasts of air from the fan. Such formation of the blades also serves to so deflect the air currents that the air is more completely diffused without the production of objectionable drafts.

What is claimed is—

1. The combination with an electric motor and a thereby carried fan, of a shaft adapted for continuous rotation disposed in supporting relation to said motor and fan, a guard carried in enclosing relation to said fan, blades pivotally mounted on said guard in front of said fan, a longitudinally adjustable member mounted on said guard, resilient means tending to hold said member in a retracted position, means for adjusting the position of said members against the tension of said resilient means, and connections between said member and said blades whereby adjustment of the former effects corresponding adjustment of the angle of inclination of said blades relative to the axis of said fan, said connections including spring cushions arranged at opposite sides of said blades.

2. The combination with an electric motor and a thereby carried fan, of a shaft adapted for continuous rotation disposed in supporting relation to said motor and fan, a guard carried in enclosing relation to said fan, blades pivotally mounted on said guard in front of said fan, a longitudinally shiftable rod carried by said guard, said rod being directed through said blades, resilient means tending to hold said rod retracted in one direction of its length, collars carried by said

rod on opposite sides of each blade, spring cushions interposed between each collar and the face of the adjacent blade, and means for shifting said rod relative to its said reTRACTING means for adjusting the angle of 70 said blades relative to the axis of said fan whereby is controlled the direction and speed of rotation of the fan-supporting shaft.

3. The combination with an electric motor and a fan carried and driven thereby, of a shaft on which said motor is mounted, a standard having said shaft mounted thereon for continuous rotation, a fixed guard enclosing said fan, blades pivoted on said guard and disposed in front of said fan, a longitudinally shiftable rod carried by said guard and having connection with each of said blades, springs carried by said rod in seated cushioning relation to opposite sides of said blades, a spring tending to hold said rod shifted in one direction, and means for effecting shifting of said rod in the opposite direction.

4. In combination with an electric fan embodying a rotary bladed element, a guard enclosing said element, air diffusing blades pivoted on said guard in front of said element, a longitudinally shiftable rod carried by said guard and having connection with said diffusing blades, elements carried by said rod in seated cushioning relation to said diffusing blades at opposite sides of the latter, a spring tending to hold said rod normally retracted in the direction of one of its ends, and means for shifting said rod in the opposite direction 100. against the force exerted by said spring.

In testimony whereof, I affix my signature.
